UNITED STATES PATENT OFFICE.

BRAYTON G. RICHARDS, OF CHICAGO, ILLINOIS, ASSIGNOR TO JACQUES ROUSSO, OF LOS ANGELES, CALIFORNIA.

TOWEL-RACK.

1,353,271.

Specification of Letters Patent. Patented Sept. 21, 1920.

Application filed March 1, 1920. Serial No. 362,428.

To all whom it may concern:

Be it known that I, BRAYTON G. RICHARDS, a citizen of the United States, and a resident of the city of Chicago, county of Cook, and State of Illinois, have invented 5 certain new and useful Improvements in Towel-Racks, of which the following is a specification.

My invention relates to improvements in 10 towel racks, and has for its objects the provision of an improved construction of this character arranged and adapted to permit of the suitable use of towels but prevent their unauthorized removal or misuse, 15 which is of simple construction, capable of economical manufacture and efficient in use.

Other objects will appear hereinafter.

The invention consists in the combinations 20 and arrangements of parts hereinafter described and claimed.

The invention will be best understood by reference to the accompanying drawings forming a part of this specification, and in which,

25 Figure 1, is a front face view of a towel rack embodying the invention,

Fig. 2, a side view of the same,

Fig. 3, a detail view illustrating the form 30 of gromet employed in the towels,

Fig. 4, a face view of a slightly modified form of construction,

Fig. 5, a side view of the same,

Fig. 6, a detail view of the form of gromet 35 employed in the towels used on the construction shown in Figs. 4 and 5, and

Fig. 7, a small detail view illustrating a modified form of towel guide member.

The form of construction illustrated in 40 Figs. 1, 2 and 3 comprises a suitable support

in the form of a wall board adapted to be secured to a wall or the like, and equipped with an upper lock 9 and a lower locking socket 10, as indicated, adapted to detach-

45 ably secure the ends of a substantially U-shaped guide member thereto. The guide member consists of a metallic strip bent into substantially U-form and having its upper

portion 11 detachably secured in the lock member 9 and extending outwardly and

50 substantially horizontally therefrom to constitute a suitable support for suspending the clean towels 12 thereon. The guide member extends thence downwardly substantially vertically to form a ver-

55 tical guide portion 13, and thence in-

wardly and downwardly to form a supporting portion 14 to support the soiled towels 15 suspended thereon, as shown. At the juncture between the portions 11 and 13 of said guide member, said guide member is 60 provided with a one-half twist 16, and the towels 12 are provided with gromets 17 having oblong openings 18 therein adapted to slide upon the guide member. By this arrangement it will be observed that a supply 65 of clean towels 12 may be readily suspended on the guide member portion 11 and removed when desired for use. In removing the towel, the same is drawn outwardly until the gromet therein strikes the twisted portion 16, whereupon the gromet and preferably the towels also are rotated around the guide member through an angle of substantially 180 degrees as the towel moves along the guide member, whereupon the 70 same is ready for use and can be used freely in the usual manner. After use, the soiled towel is simply released and the same falls to the lower portion of the guide member portion 13 of its own weight, and may be 75 then pushed back along the portion 14 to the position indicated.

The form of construction illustrated in Figs. 4, 5 and 6 is identical with that described, except for a slightly different arrangement of the twist in the guide bar. In this form of the construction the guide bar is given a quarter twist 18 at the outer end of the portion 11, and another quarter twist 19 at the lower portion of the guide member portion 13. By this arrangement, enough of a twist is provided at the point 18 to prevent too easy disarrangement of the clean towels from their position on the guide member portion 11, and the towels are 90 again properly positioned by the twist 19 for free hanging on the guide member portion 14.

In the form of construction illustrated in Fig. 7, a guide rod 20 is employed instead 100 of the guide bar as previously described, and this guide rod is provided with a transverse pin 21 at the outer end of the upper horizontal portion thereof to prevent the too easy removal of the clean towels. The 105 gromet 17 is provided with a circular central perforation to slide freely on the rod 20, and with vertical extensions 22 to pass over the pin 21, when the towel or the gromet is rotated or revolved through an angle of sub- 110

stantially ninety degrees. Otherwise, the construction and operation is identical with that disclosed in Figs. 1, 2 and 3.

While I have illustrated and described the preferred forms of construction for carrying my invention into effect, these are capable of variation and modification without departing from the spirit of the invention. I, therefore, do not wish to be limited to the precise details of the construction set forth, but desire to avail myself of such variations and modifications as come within the scope of the appended claims.

Having described my invention, what I claim as new and desire to secure by Letters Patent is:—

1. A towel rack comprising a towel guide member adapted to hold towels provided with securing members sliding on said guide member; and means on said guide member and said securing members compelling relative rotation of said securing members and said guide member during movement of said securing members along said guide member, substantially as described.

2. A towel rack comprising a towel guide member oblong in cross section and twisted at one point and adapted to hold towels provided with securing members having oblong openings therein to slide on said guide member, substantially as described.

3. A towel rack comprising a towel guide member twisted at one point and adapted to hold towels provided with securing members having openings therein to slide on said guide member, substantially as described.

4. A towel rack comprising a towel guide strip having a substantially horizontally extending portion and a twisted portion adjacent the outer end of said horizontally extending portion and adapted to hold towels suspended on said horizontally extending portion having securing members provided with openings sliding on said strip, substantially as described.

5. A towel rack comprising a support; a towel guide member consisting of a strip of metal bent into substantially U-form and having its ends detachably secured to said support, the upper limb of said guide mem-

ber extending outwardly substantially horizontally from said support and having a twist therein at the outer end of said horizontally extending portion, said strip extending thence downwardly substantially vertically and thence inwardly to said support and adapted to hold towels having gromets therein suspended on the horizontal portion of said strip, said gromets having oblong openings sliding on said strip, substantially as described.

6. A towel rack comprising a support; a towel guide member consisting of a strip of metal bent into substantially U form and having its ends detachably secured to said support, the upper limb of said guide member extending outwardly substantially horizontally from said support, thence downwardly substantially vertically and thence inwardly to said support, there being a twist in said guide member at the juncture between said upper limb and said vertical portion thereof and adapted to hold towels having gromets therein suspended on the horizontal portion of said strip, said gromets having oblong openings sliding on said strip, substantially as described.

7. A towel rack comprising a support; a towel guide member consisting of a strip of metal bent into substantially U form and having its ends detachably secured to said support, the upper limb of said guide member extending outwardly substantially horizontally from said support, thence downwardly substantially vertically, and thence inwardly to said support, there being a twist in said strip at both the junctures of the upper and lower limbs with said vertical portion and adapted to hold towels having gromets therein suspended on the horizontal portion of said strip, said gromets having oblong openings sliding on said strip, substantially as described.

In testimony whereof I have signed my name to this specification in the presence of two subscribing witnesses.

BRAYTON G. RICHARDS.
